REVERSIBLE AND BERTHABLE SEAT

Benjamin F. Monroe, Los Angeles, Calif., assignor
to Lockheed Aircraft Corporation, Burbank,
Calif.

Application November 25, 1946, Serial No. 712,119

15 Claims. (Cl. 155—6)

1

This invention relates to vehicle seating, with particular reference to seats adjustable for reclining, reversing and berthing positions. While my seats are particularly designed for use in airplanes, and will be so disclosed herein, it will be evident that they are equally suitable for use in railroad cars, highway busses, and other installations wherein adjustable and berthable seats are desirable.

In airplane installations, it is desirable to have a central aisle with one or more rows of seats on either side thereof. For convenience in disclosing my invention I have a single row of seats, but it is to be understood that as many rows can be placed side by side as may prove desirable in any particular installation. Usually, two rows will be used wherein a group of four chairs can be made up into either two single, or one double berth, as may be desired by the occupants, since one occupant may prefer a berth and the other prefer a reclining chair. With chairs constructed according to my invention, aligned chairs of any two adjacent rows may be made up into a berth, and each chair of any row may be reversed or reclined, regardless of the position of the other chair or chairs in the same or adjacent rows.

It is, accordingly, an important object of this invention to provide a reversible, reclining and berthable chair construction which will permit all the chairs in the same or adjacent or successive rows to be operationally identical and interchangeable, above the base sections secured to the floor.

It is also an object of this invention to provide an improved and simplified chair of the character described wherein the seat and back are identical and interchangeable, the seat being transposed to become the back, and vice versa, when the chair is reversed to face the other way. With this arrangement the seat and back frames need be cushioned only on one side, permitting a decrease in thickness and in weight, while the bottoms or backs of both members may be recessed to provide more knee room for the occupant of the next seat.

It is a further object of this invention to provide an improved and simplified chair of the type described which comprises four major units, namely, a base fixed to the floor, seat and back panels pivoted together and having the pivot points thereof slidable in suitable guide-ways in the base, removable, reversible and interchangeable arm rests cooperating with the seat and back panels to hold the latter in their several

adjusted positions, and removable head rests usable with either cushion.

It is another object of this invention to provide, in a chair of the character described, pivotally interconnected and identical seat and back frames having identical and interchangeable seat and back cushions slidably mounted on said frames and so arranged that whichever cushion is serving as the seat is locked relative to its frame, while the other cushion is slidable relative to its frame and moves relative thereto as the angle of the seat back is changed.

It is still another object of this invention to provide an improved and simplified seat of the type described wherein the seat and back frames are pivoted together at a point near the adjacent edges of the seat cushions and the gap between the cushions is closed by an elastic flap to prevent a passenger from inserting his toes between the cushions of the chair ahead of him. The flap also facilitates the desired downward movement of the back cushion when the back is being tilted or reclined.

It is a further object of this invention to provide pivoted seat and back frames on which the cushion serving as a back is movable and wherein the seat and back cushions are connected by an extensible compression strut adapted to push the back cushion upwardly on its frame when it is being erected from the reclined position.

It is also an object of this invention to provide a convertible chair construction of the type described wherein the several parts of the chair are readily assembled and removed without the use of tools for ease in installation and servicing thereof.

Other objects and features of the invention will be readily understood from the following detailed description of typical preferred forms of the invention wherein reference will be made to the accompanying drawings in which:

Figure 1 is a side elevation of adjacent chairs, either of which can be reversed, or together combined into a berth, the chair at the left being shown in full lines in its erect position and in dotted lines in inclined berthable position, and the chair at the right being shown in full lines in erect position facing to the left and in dotted lines in erect position but facing to the right;

Figure 2 is a rear perspective view, partly broken away, and showing on an enlarged scale a chair built according to one embodiment of this invention;

Figure 3 shows the chairs of Figure 1 made up into a berth;

2

Figure 4 is a detail section of one of the adjustable arm rests for controlling the inclination of the back of the chair;

Figure 5 is an end fragmentary detail of the friction lock in the arm rest of Figure 4;

Figure 6 is a fragmentary inside perspective detail of the hinged connection between the seat and back frames and the compression tie rods between the seat and back cushions slideable on their respective frames;

Figure 7 is a perspective view, partly broken away, of an alternative form of the adjustable arm rest mechanism;

Figure 8 is a fragmentary outside perspective view, similar to Figure 6, showing the seat and back frames and cushions with the arm rest removed;

Figure 9 is a fragmentary detail section showing the cushion latch release mechanism with the head rest in place; and,

Figure 10 is an exploded rear perspective view of a chair assembly.

The seat construction of this invention comprises a base structure A, including legs 15 and cross ties 16; removable master and slave arm rests 17 and 18, which engage and lock into the base structure; identical seat and back cushions 19 and 20, separately numbered for convenience in tracing their positions when the seat direction is reversed, and a removable head rest 21, which can be applied to whichever cushion, 19 or 20, is serving as the back cushion.

Two or more side-by-side seats will ordinarily be used in a given row, although only one seat is shown in the drawings to avoid complications; and the intermediate legs 15' can conveniently serve both adjacent seats. It will be understood that they are removably secured to the floor B of the vehicle, with adjacent rows properly spaced to afford sufficient knee room, and whereby tandem seats cooperate to form a horizontal berth when the cushions are arranged therefor.

The identical seat and back cushions 19 and 20 are built up on bases 22 having side channels or boxes 23 in which frame members 24 are slideable, the frame members being hinged together at 25 with the hinge pins 26 formed with rollers 27 engageable in horizontal guide-ways 28 in the base structure, as best shown in Figures 6, 8, and 10. While the hinge rollers 27 are movable in the guide-ways 28, they are ordinarily positioned at one end or the other, according to which way the seat is set to face.

Each frame member 24 carries a pin 29 projecting through one of the slots 30 in the side channels 23 of the cushion bases, the pins 29 on the back cushion normally engaging in sockets 31 carried by the arm rests. The pins 29 on the seat cushion normally enter the bottoms of scroll-like slots in guide sockets 32 carried by the arm rests, to support the seat cushion at a suitable angle; but when the seat is to be level as part of a berth, the seat and its frame are manipulated to release the pins 29 on the seat frame from the guide sockets 32 on the arm rests, and the seat frame is then pushed down to cause the pins 29 to drop through the slots 33 into the guide ways 28 in the base structure, which guide ways also normally support the hinge rollers 27, as shown in Figure 8, thus leveling the seat frame and its cushion.

As so far described, both the seat and back cushions are slideable on the frame members 24 within the limits defined by the slots 30 in the side channels 23 of the cushion bases. In order

to hold the cushion, which serves as a seat, from back and forth movement, a pin 34 on the side channel (shown in Figure 8) can engage a detent 35 on the arm rest (shown in Figure 7). In order to hold the seat against the back and forth movement on its frame members 24, a latch (Figure 9) can be used instead of pin 34 and detent 35. The latch comprises a pivoted spring pressed latch arm 36 engageable in two positions relative to the free end of one of the frame members 24, one detent 37 close to the pivot point of the arm, engaging in a notch 38 in the frame member 24 to hold the seat cushion retracted, and a second detent 39 engaging in the same notch to hold the seat cushion 19 extended to facilitate reversing the seat direction. A thumb button 40 enables manual release of either detent, and when the cushion becomes the back, insertion of the head rest 21 causes a dowel 41 carried thereby to contact a plunger 42 to automatically release the second detent 39 from the notch, permitting the cushion to slide up and down on the frame member with the notch 38 on the frame member located between the two detents under control of mechanism to be later described, which mechanically shifts the back cushion as the angle thereof is changed.

The seat and back cushion bases 22 are linked together by an elastic cloth closure 43, the primary purpose of which is to prevent a passenger in the next row of seats from placing his toes in the gap between the seat back cushions. The elastic tension in this closure also helps to pull down the back cushion base when the back is being adjusted. A freely extensible two part telescoping compression resisting strut 44 also connects the two cushion bases 22 and serves to push the base upwardly on its frame member when the back is being returned from the reclining position to the erect position.

Control of the angular position of the back is through the adjustable arm rest caps 45 which are attached to the back frame pins 29 at the sockets 31. While either or both arm rests (Figs. 4 and 7) can control the back position, I have shown a single lock in Figure 4 and locks in both arm rests in Figure 7, wherein a single manual release in one master arm rest 17 controls the lock in the slave arm rest 18. Figures 4 and 7 show alternative forms of locking arm rests which are functionally similar, with Figure 4 using linkage, while Figure 7 uses flexible Bowden wires. In both forms the arm rest cap is slideable and tiltable as the seat back is moved, the rear end, which carries the socket 31, being supported at 45a by a link rod 46 pivoting about a point 46a in the arm rest normally in approximate vertical alignment with the frame pin 26. In Figure 4 the arm rest cap has a pivot at 47. Each cap 45 is a shell having an open bottom and two parallel sides connected to or integral with a top member; and the slot or guideway 49 is provided in one of such parallel sides. The forward end of the arm rest cap 45 carries a pivoted finger lever 50 which actuates a friction locking lever 51 that slides on a rod 52. The locking lever 51 is pivotally secured to one of the parallel sides of the cap 45. In Figure 4 the rod 52 fulcrums at 47 on the relatively fixed part 17' of the arm rest; and a seat back return and lock-engaging spring 54 is positioned on the rod between a collar 55 slideable thereon and an end collar 56. With this arrangement, release of the friction lock lever 51 allows the spring 54 to push the arm rest cap forwardly to pull the seat back erect.

In the form of Figure 7 the finger lever 50a pulls a Bowden wire 57 acting on a bell crank 58, in turn operating a second Bowden wire 59 to release the friction locking lever 51a which slides on the rod 52a, which rod is pivoted to the arm rest cap at 60. In this case the return spring 54a also engages between the collar 53a and an end collar 56a. The locking lever 51a is pivoted, as denoted at 75, in the relatively stationary part 17' of the arm rest; and it has a pin 48 integral with it that engages in a slot or guideway 49 in the arm rest cap 45a. In this case, the arm rest cap comprises a shell portion 76 and a rear casting 77. The shell portion 76 has an open bottom and two parallel sides. Casting 77 has a forwardly projecting portion 78 at one side which extends beneath side 79 of shell portion 76 and which is welded thereto and constitutes the remainder of one side of the cap. Casting 77 has a median rib 80 between its two sides which is furcated and to which rod 52a and link rod 46 are pivoted by pin 60.

Figure 7 also shows a master control for the other or slave arm rest 18 comprising a spring-loaded plunger 61 which projects through a hole 70 (Figs. 8 and 10) in the associated leg 15 and which is lifted when the bell crank 58 is actuated, as described in the preceding paragraph upon movement of the finger lever 50a. The plunger 61 rests on an arm 62 which is secured to a spring-loaded cross shaft 63 that is journaled in the base structure. A coil spring 64 that engages at one end with the leg 15 and at its opposite end with the arm 62 constantly urges the shaft 63 counter-clockwise about its axis as viewed in Fig. 7. A duplicate plunger in the slave arm rest contacts an arm on the shaft 63, which is a duplicate of the arm 62, to actuate through a bell crank and Bowden wire, similar to bell crank 58 and Bowden wire 59 a friction locking lever similar to the lever 51a.

In the operation of the chair described, reference will first be had to Figure 1 wherein the left-hand chair is shown in full lines set up in the erect position facing the right, and the right-hand chair, as shown in full lines, is set up to face the left. The dotted lines show how the right-hand chair can be reversed to face to the right. In so reversing the chair, the back cushion 20 moves down to become the seat cushion 19' and the erstwhile seat cushion 19 is tilted up to become the back cushion 20', the entire construction of the seats and backs being symmetrical and interchangeable about the hinge pin 25.

In reversing the seat, the seat base 22 has its pins 29 released from the guide sockets 32 by manipulation of the seat to move the pins 29 out of the sockets 32. The arm rests are then removed from the base structure after manual release of the latch 64 best shown in Figure 7. The head rest is preferably pulled out of the back and set aside. By grasping the outer ends of the seat and back cushions they may be held in a V like form limited by the link 44, the hinge pins 25 and their rollers 27 shifted to the other ends of the guideways 28 in the base to transpose the erstwhile back cushion into the seat cushion for the reversed chair, the former seat cushion being lifted or pivoted about the hinge pins 25 to form the back cushion. Reversing and interchanging the arm rests 17 and 18, engaging the seat pins 29 with the guide sockets 32 thereon, and the back pins 29 with the sockets 31 carried by the arm rest caps, completes the chair reversal, except for replacing the head rest.

In Fig. 1 the chair at the left is shown in full lines in erect position with the seat cushion tilted, and it is shown in dotted lines during conversion into a reclining berth with the seat cushion flat. In this latter arrangement, the head rest may be applied to the seat cushion to further extend the same. As described elsewhere and shown in Figure 9, the seat cushion base 22 has its side channels 23 normally locked at the innermost position relative to the frame members 24 and the seat cushion is supported at a slight angle relative to the base for added comfort. In its tilted position the seat remains fixed, while the back cushion is being tilted back to the dotted line position of the left hand chair of Figure 1, and because the back cushion is free to slide on its frame members 24 as permitted by the strut 44 connecting the two cushion bases, it slides down on its frame members. Since the pivot points or hinges 25 between the cushion bases is to the rear of the back cushion, the lower edge of the back cushion moves back or away from the seat cushion to expose approximately two more inches, thus in effect, lengthening the seat. This extra effective seat length conforms to anatomical requirements so that a seated passenger changing from the erect to reclining position, or vice versa, does not have to shift his seated position. Since a flat seat would be preferable if the passenger desires to nap in the reclined position, the seat cushion pins 29 may be released from the bottom of the scroll-like slots in the guides 32 by suitable manipulation of the seat cushion and its frame 24. Ordinarily the arm rests carrying the guides 32 will be removed at this point, and the seat and its frame 24 further manipulated to lower the pins 29 through the slots 33 into the guideways 28. However, since the bottom openings in the slots in the guides 32 line up with the slots 33 in the base, the seat can be lowered to the level position without removing the arm rests. The seat cushion frame 23 is then unlatched from the frame members 24 and drawn out to its extended position, the outward movement of the seat permitting lowering of the back cushion on its frame members, as shown by the dot and dash lines associated with the dotted line reclined position of Fig. 1.

When the back cushion and its frame members are being adjusted, the arm rest caps move and tilt therewith, being attached to the frame members at the pin 29. The adjustment of the back cushion and its frame members is under the control of the arm rest cap mechanism, the passenger lifting the finger lever 50 to release the locking lever 51 and leaning back to push the seat back against the force of the spring 54, or leaning forward to allow the spring 54 to bring the back to the erect position.

When two seats are to be made up into a single flat berth, as shown in Figure 3, the seat cushion of the left chair is lowered and extended, thus disengaging its pins 29 from the arm rests and the head rest 21 from the back is applied thereto to form part of the berth. The right-hand chair can have either or both of its arm rests 17 and 18 removed. To remove either arm rest the latch 64 (Figs. 3 and 10) is released. Each latch 64 is adapted to engage in a slot 67 in the associated leg 15 or 15', as the case may be. The latch is disengaged by pressing an associated thumb button 65, such as shown in Figure 7. The arms, after removal, may be stowed between the legs 15 and 15' of the base. Each

arm rest is properly located on the supporting leg structure by spaced pins 68 (Fig. 10) which engage in holes 69 in the associated leg.

When it is desired to reverse the direction the seat faces, as shown in dotted lines in connection with the right-hand chair in Figure 1, both arm rests are removed, and the seat and back cushions are moved simultaneously until they become the back and seat cushions respectively, each hinge roller 27 moving to the left end of its guide-way in the base. The arm rests are then both turned end-for-end and refastened to the base of the chair, being applied to the proper sides so that they face in the new direction. The head rest 21 is removed from the former back cushion and applied to the new one, preferably being removed before the cushions are shifted and being replaced thereafter.

It will be evident from the foregoing that my seat construction is readily reversible and convertible into either a flat or reclining chair, as may be desired, and that as a chair the arm rests are properly positioned for comfort regardless of the position of, or the direction the chair faces. Moreover, the various parts are completely interchangeable and reversible as to position and function.

Having described only typical forms of the invention, I do not wish to be limited to the specific details herein set forth, but wish to reserve to myself any variations or modifications that may appear to those skilled in the art and as fall within the scope of the following claims.

I claim as my invention:

1. A convertible and reclining chair comprising a base structure having guide-ways therein, cushions interchangeable between the seat and back positions on said base structure, frame members supporting said cushions and hingedly connected together between said cushions, means carried by the hinged connection between said frame members adapted to movably secure said connection to said guideways, arm rests carried by said base structure, means carried by said arm rests engaging said frame members whereby to support said seat and back cushions at the desired angles to each other, means for adjusting the supporting means whereby to change the angle of the chair back, means releasably attaching said arm rests to said base structure so arranged that the arm rests are interchangeable and reversible whereby the chair can be set to face in either direction with either cushion forming the seat and the other cushion forming the back according to which way the chair faces.

2. A convertible and reclining chair comprising a base structure having guide-ways therein, cushions interchangeable between the seat and back positions on said base structure, frame members supporting said cushions and hingedly connected together between said cushions, means carried by the hinged connection between said frame members adapted to movably secure said connection to said guideways, arm rests carried by said base structure, means carried by said arm rests engaging said frame members whereby to support said seat and back cushions at the desired angles to each other, means for adjusting the supporting means whereby to change the angle of the chair back, means releasably attaching said arm rests to said base structure so arranged that the arm rests are interchangeable and reversible whereby the chair can be set to face in either direction with either cushion

ion forming the seat and the other cushion forming the back according to which way the chair faces, and sliding caps forming part of the means carried by the arm rests and arranged to follow the motion of the back cushion.

3. A convertible and reclining chair comprising a base structure having guide-ways therein, cushions interchangeable between the seat and back positions on said base structure, frame members slidably supporting said cushions thereon and hingedly connected together between said cushions to vary the angle between said cushions, strut means connecting said seat and back cushions and biasing the hinged connection between the frame members whereby angular changes at the hinged connection produce sliding movements of one cushion relative to its frame member, means carried by the hinged connection between said frame members adapted to movably secure said connection to said guideways, arm rests carried by said base structure, means carried by said arm rests engaging said frame members whereby to support said seat and back cushions at the desired angles to each other, means for adjusting the supporting means whereby to change the angle of the chair back, means releasably attaching said arm rests to said base structure so arranged that the arm rests are interchangeable and reversible whereby the chair can be set to face in either direction with either cushion forming the seat and the other cushion forming the back according to which way the chair faces.

4. In a chair of the character described a base structure, arm rests supported by said base structure, seat and back frame members hinged together intermediate the seat and back, means for supporting said frame members from the base structure at the hinge connection therebetween and from the arm rests at points spaced from the hinge connection, seat and back cushions slidably lengthwise upon said frame members, means for latching the seat cushion to its frame member, and strut means connecting said seat and back cushions in biasing relationship to the hinge connection between the frame members, whereby angular movements of the back cushion and its frame member relative to the seat cushion and its frame member move the back cushion along its frame member.

5. In a chair of the character described a base structure, arm rests supported by said base structure, seat and back frame members hinged together intermediate the seat and back, means for supporting said frame members from the base structure at the hinge connection therebetween and from the arm rests at points spaced from the hinge connection, seat and back cushions slidably lengthwise upon said frame members, means for latching the seat cushion to its frame member, and strut means connecting said seat and back cushions in biasing relationship to said hinge connection, whereby movement of the back cushion and its frame member relative to seat cushion and its frame member move the back cushion along its frame member, and means carried by said arm rests adapted to adjustably control the angular position of the cushion serving as a back rest.

6. In a chair of the character described a base structure, detachable and reversibly interchangeable arm rests removably supported by said base structure, seat and back frame members hinged together intermediate the seat and back, means for removably supporting said frame

members from the base structure at the hinge connection therebetween and from the arm rests at points spaced from the hinge connection, seat and back cushions slidably lengthwise upon said frame members, means for latching the seat cushion to its frame member, and strut means connecting said seat and back cushions in biasing relationship to the hinge connection between the frame members, whereby angular movements of the back cushion and its frame member relative to the seat cushion and its frame member move the back cushion along its frame member, whereby detaching, reversing and transposing said arm rests and transposing said cushions relative to said base structure effects reversing the direction in which said chair faces.

7. In a chair of the character described a base structure, arm rests supported by said base structure, seat and back frame members hinged together intermediate the seat and back, means for supporting said frame members from the base structure at the hinge connection therebetween and from the arm rests at points spaced from the hinge connection, said arm rests comprising a fixed support for the seat frame member and an adjustable support for the back frame member, each adjustable support including a movable cap for the arm rest, means carried by said cap in association with said arm rest for controlling the adjustment of said adjustable support whereby to vary the angle of the seat back, seat and back cushions slidably lengthwise upon said frame members, means for latching the seat cushion to its frame member, and strut means connecting said seat and back cushions in biasing relationship to the hinge connection between the frame members, whereby angular movements of the back cushion and its frame member relative to the seat cushion and its frame member move the back cushion along its frame member.

8. In a chair of the character described, a seat and a back, each having a frame member, hinge means connecting said frame members intermediate the seat and back and permitting angular adjustments between the seat and back including a level berthing position, a base, means on said base for providing a support for said frame members at the hinge means thereof, an arm rest carried by said base and including a stationary support, means for releasably securing said stationary support to said base, means connecting the seat frame member to said stationary support in spaced relation with respect to said hinge point, and an adjustable cap carried by said stationary support and connected to said back frame in spaced relation with respect to said hinge means for controlling the adjustment of the angle of said back frame member.

9. In a chair of the character described, a seat and a back, each having a frame member and a cushion and at least one of said cushions being longitudinally adjustable with respect to its frame member, hinge means connecting said frame members intermediate the seat and back and permitting angular adjustments between the seat and back including a level berthing position, a base, means on said base for providing a support for said frame members at the hinge means thereof, an arm rest carried by said base and including a stationary support, means for releasably securing said stationary support to said base, means connecting the seat frame member to said stationary support in spaced rela-

tion with respect to said hinge means, and an adjustable cap carried by said stationary support and connected to said back frame member in spaced relation with respect to said hinge means for controlling the adjustment of the angle of said back frame member.

10. A reversible, reclining, and berthable seating arrangement comprising a base structure having parallel spaced guideways, seat and back frames, hinge means connecting said frames, members aligned with the axis of rotation of said hinge means and movably and pivotally mounted in said guideways, identical seat and back cushions supported by and separately slidably on said seat and back frames respectively, arm rests removably secured to said base structure, and means carried by said arm rests engaging other means on each of the respective frames to support same with one frame and its cushion providing a back portion and the other frame and its cushion forming a seat portion, said frames being bodily shiftable along said guideways to a location in which they may be rocked on said members to reverse their positions, whereby either one of said cushions may be supported at a suitable angle to form a seat cushion while the other of said cushions forms a back cushion.

11. A reversible, reclining, and berthable seating arrangement comprising a base structure having parallel spaced guideways, seat and back frames, hinge means connecting said frames, members aligned with the axis of rotation of said hinge means and movably and pivotally mounted in said guideways, identical seat and back cushions supported by and separately slidably on said seat and back frames respectively, arm rests removably secured to said base structure, and means carried by said arm rests engaging other means on each of the respective frames to support same with one frame and its cushion providing a back portion and the other frame and its cushion forming a seat portion, said frames being bodily shiftable along said guideways to a location in which they may be rocked on said members to reverse their positions, whereby either one of said cushions may be supported at a suitable angle to form a seat cushion while the other of said cushions forms a back cushion.

12. A reversible, reclining, and berthable seating arrangement comprising a base structure having parallel spaced guideways, seat and back frames, hinge means connecting said frames, members aligned with the axis of rotation of said hinge means and movably and pivotally mounted in said guideways, identical seat and back cushions supported by and separately slidably on said seat and back frames respectively, arm rests removably secured to said base structure, and means carried by said arm rests engaging other means on each of the respective frames to support same with one frame and its cushion providing a back portion and the other frame and its cushion forming a seat portion, said frames being bodily shiftable along said guideways to a location in which they may be rocked on said members to reverse their positions, whereby either one of said cushions may be supported at a suitable angle to form a seat cushion while the other of said cushions forms a back cushion, the first-named means comprising movable caps carried by said arm rests and having pivotal connections to the frame carrying the back cushion whereby said caps move as

said back cushion and its frame is tilted to different angles, and means for locking said caps against movement to secure the respective back frames in the tilted positions to which they are adjusted.

13. A reversible, reclining, and berthable seating arrangement comprising a base structure having parallel spaced guideways, seat and back frames, hinge means connecting said frames, members aligned with the axis of rotation of said hinge means and movably and pivotally mounted in said guideways, identical seat and back cushions supported by and separately slidable on said seat and back frames respectively, arm rests removably secured to said base structure, and means carried by said arm rests engaging other means on each of the respective frames to support same with one frame and its cushion providing a back portion and the other frame and its cushion forming a seat portion, said frames being bodily shiftable along said guideways to a location in which they may be rocked on said members to reverse their positions, whereby either one of said cushions may be supported at a suitable angle to form a seat cushion while the other of said cushions forms a back cushion, the first-named means comprising movable longitudinally elongated caps carried by said arm rests and having pivotal connections to the frame carrying the back cushion whereby as said caps move along said arm rests, said back cushion and its frame is tilted to different angles, and locking means carried by said caps for adjustably controlling the angular position of the part of the frame carrying the back cushion.

14. A reversible, reclining and berthable seating arrangement comprising a base structure having parallel spaced guideways, seat and back frames, hinge means connecting said frames, members aligned with the axis of rotation of said hinge means and movably and pivotally mounted in said guideways, identical seat and back cushions supported by and separately slidable on said seat and back frames respectively, means for locking each cushion to its frame when said cushion is used as a seat cushion, said means being arranged for actuation to free said cushion for sliding motion relative to its frame when used as a back cushion, strut means bracingly connecting said cushions relative to the hinge means whereby to cause sliding motion of the back cushion relative to its frame as the angle of the back cushion in relation to the seat cushion is altered, arm rests removably secured to said base structure, and means carried by said arm rests engaging other means on each of the respective frames to support same with one frame and its cushion providing a back portion and the other frame and its cushion forming a seat portion, said frames being bodily shiftable along said guideways to a

location in which they may be rocked on said members to reverse their positions, whereby either one of said cushions may be supported at a suitable angle to form a seat cushion while the other of said cushions forms a back cushion.

15. A reversible, reclining, and berthable seating arrangement comprising a base structure having parallel spaced guideways, seat and back frames, hinge means connecting said frames, members aligned with the axis of rotation of said hinge means and movably and pivotally mounted in said guideways, identical seat and back cushions supported by and separately slidable on said seat and back frames respectively, means for locking each cushion to its frame when said cushion is used as a seat cushion, said means being arranged for actuation to free said cushion for sliding motion relative to its frame when used as a back cushion, strut means bracingly connecting said cushions relative to the hinge means whereby to cause sliding motion of the back cushion relative to its frame as the angle of the back cushion in relation to the seat cushion is altered, arm rests removably secured to said base structure, and means including movable caps carried by said arm rests and having pivotal connection with one of said frames to support the same with its cushion providing a back portion and means carried by said arm rests engaging other means on the other frame to support the latter with its cushion forming a seat portion, said frames being bodily shiftable along said guideways to a location in which they may be rocked on said members to reverse their positions, whereby either one of said cushions may be supported at a suitable angle to form a seat cushion while the other of said cushions forms a back cushion, and whereby said caps move as said back cushion and its frame is tilted to different angles, and means carried by said caps for adjustably controlling the angular position of the frame carrying the back cushion.

BENJAMIN F. MONROE.
